UNITED STATES PATENT OFFICE.

JULIAN R. HOLLEY, OF BRISTOL, AND EVERETT D. HOLLEY, OF FORESTVILLE,
CONNECTICUT.

HEATING DEVICE.

No. 926,188.

Specification of Letters Patent.

Patented June 29, 1909.

Application filed September 3, 1908. Serial No. 451,944.

To all whom it may concern:

Be it known that we, JULIAN R. HOLLEY and EVERETT D. HOLLEY, citizens of the United States, and residents of Bristol and 5 Forestville, respectively, in the county of Hartford and State of Connecticut, have invented certain new and useful Improvements in Heating Devices, of which the following is a full, clear, and exact specification.

This invention relates to heating devices, and more particularly to that type in which an electric resistance conductor is employed as the heat-developing element, and it has 15 for one of its objects the provision of a unit-device of this character, which may be readily connected into a circuit, and in which the liability to damage from overheating is practically obviated.

Our invention has, furthermore, for its object the provision of a flat-face until the entire heating surface of which is heated in a substantially uniform degree, so that the diffusion of the heat will be equal on all 25 parts thereof.

Our invention has, furthermore, for its object the improved manner of attaching the unit to a vessel to be heated.

Briefly stated, our invention comprises an 30 electrical heat-unit having a flat contact surface with the article to be heated, this flat surface being formed by a thin layer of mica which insulates or protects the heat-imparting medium or wire from short-circuit. This wire is in the present instance in 35 the form of a ribbon which is laid flatwise on a body of insulating material and the several runs or adjacent layers of which are substantially disposed in parallelism so as 40 to provide a clearance space of sufficient width to prevent arcing.

In the accompanying drawings, in which similar characters denote similar parts. Figure 1 is a vertical section of a unit embodying our invention applied to the bottom plate of a vessel or dish, and Fig. 2 represents a horizontal section on line 2, 2 of Fig. 1.

In the drawings, 10 denotes the bottom of 50 a vessel or pot which has secured thereto a heat-concentrating base plate 11 with which our improved heat-unit is adapted to come into direct contact. The unit comprises, in its preferred form, a disk 12, made of in-

sulating material such as for instance soap 55 stone, the upper face of which contains the heating medium which consists of a flat ribbon wire 13 of conducting material in such proportions as to offer a substantial resistance to the passage of the current. The wire ribbon 13 may be formed either by winding the same edgewise into spiral form, as shown in Fig. 2, or the entire resistance member may be produced by punch-and-die process so as to have the several adjacent runs or convolutions in parallelism and separated by air spaces to prevent short-circuit and the consequent loss of resistance and heat. The disk 12 has apertures 15, 16, through which the ends of the 60 resistance wire pass to a point below said disk which may be comparatively thin and then reinforced by a plate 20 also preferably made of soap stone and having ribs 21 for supporting the central portions of the disk 70 12 which may be otherwise separated therefrom by air-spaces 22 to avoid the radiation of heat. The resistance ribbon 13 is covered by a thin layer of mica 25 which serves as an insulator to guard the ribbon 80 against contact with the metal base plate 11, while at the same time its thickness will not preclude a rapid and thorough heat penetration to the lower surface of said base plate.

In order to render the unit self-contained, we prefer to employ the consolidation of the several parts as shown in Fig. 1, in which the soap stone-base 20, the resistance-carrying disk 12, and mica insulator 25 are 90 represented assembled within a cup-shaped shell 26 and drawn together therewith by screw-threaded bolts 27 having flanged heads 28 and nuts 29.

Passing through the tubular bolts 27, are 95 screws 30 which are threaded in the base plate 11 and serve to bring the entire unit and more especially its upper surface into contact with the bottom of the base plate 11.

Many changes may be made in the formation of the resistance ribbon, which in the present instance is formed in the shape of a spiral, substantially the same results being obtained when the ribbon is formed zig-zag or in serpentine form.

The terminals for connecting the unit to the main wires of a power-current, may be of any desired construction, the drawing

representing only the ends of the resistance ribbon as they protrude from the insulator casing.

We claim:

5. 1. A heat-unit comprising a resistance-ribbon wound flatwise into a series of successive convolutions which are separated from each other by substantially-uniform air spaces, whereby the diffusion of heat from
10 said resistance ribbon will be substantially uniform over the entire surface thereof.
2. A heat-unit consisting of an insulating

body, a resistance-ribbon resting flatwise thereon and wound flatwise to form a series of continuous spiral convolutions separated 15 from each other by substantially-uniform air spaces to prevent short circuit, and a cover of electric insulating and heat conducting material over said resistance ribbon.

JULIAN R. HOLLEY.
